ANTISPILL DEVICE FOR LIQUID CONTAINERS

Wallace S. Dale, Minneapolis, Minn.

Application April 3, 1948, Serial No. 18,736

2 Claims. (Cl. 65—13)

1

This invention relates to device for preventing spilling from liquid containers.

It is the general object of my invention to provide a device adapted to be attached to a liquid container to prevent spilling of liquid therefrom even though the container is tipped.

It is another object to provide a simple and highly efficient top closing device for liquid containers to normally close the same but adapted to be controllably opened to permit liquid to flow therefrom.

It is a further object to provide a top closure device for liquid containers for normally closing the same and having a valve mechanism adapted to be opened by lifting of the container by a shiftable gripping device connected to said valve.

More specifically it is an object of my invention to provide a top closure device for liquid containers having a controllable valve therein to prevent air from entering the same and a handle member for holding said container, mounted in sliding relation thereto and connected with said valve for opening the same when said container is lifted by said handle, said valve being normally closed to prevent spilling of liquid from said container when negligently tipped.

These and other objects and advantages of my invention will more fully appear from the following description made in connection with the accompanying drawings wherein like reference characters refer to similar parts throughout the several views and in which:

Fig. 1 is a side elevational view of the device embodying my invention;

Fig. 2 is a top plan view of the device shown at Fig. 1;

Fig. 3 is a central vertical sectional view taken substantially on the line 3—3 of Fig. 2 and showing the valve mechanism in detail; and

Fig. 4 is a horizontal sectional view taken substantially along the line 4—4 of Fig. 3.

As illustrated in the accompanying drawings I provide a top closure device designated as an entirety by the numeral 6 for liquid containers such as a drinking cup 7 and the like adapted to be suitably attached in sealed relation thereto as by being threadably mounted thereon to form a normally closed drinking container. The closure 6 has a horizontally disposed partition 8 fixed therein and the partition 8 has outlet means such as the apertures 9 formed at the outer marginal portion thereof. An air vent 10 is formed in said partition 8 in spaced relation to said outlet aperture 9 as by being disposed in 90° angular displacement therefrom as illustrated in Fig. 2. The

2

air vent 10 has a valve seat 11 formed at the outer portion thereof.

A mounting bracket 12 is fixed in the form illustrated to the closure 6 which forms an integral unit with the cup 7 when secured thereto as best shown in Fig. 4. Bracket 12 has a guide or trackway 13 formed in the outer marginal portion thereof and slide 14 is mounted for vertical sliding movement in said trackway and has a gripping handle 15 fixed thereto. A connector arm 16 extends inwardly from the top of slide 14 to which it is fixed as by a screw 17 and has a valve 18 fixed at the inner end thereof in alignment with air vent aperture 10. A cooperating sealing element on the valve 18 is adapted to be normally seated against the valve seat 11 of the vent 10 to normally close said vent. A downwardly extending projection 19 is fixed to the bottom of said valve 18 and depends from the central portion thereof to guide said valve into proper position within said vent 10. A resilient spring 20 is fixed at one end of said arm 16 and at the other end to an outstanding element 21 fixed to said closure 6 and normally urges said valve 18 into its seat 11. Fig. 3 shows the valve 18 in open position.

The tension in spring 20 is such that the slide 14 will be shifted upwardly against said tension whenever the container 7 has liquid therein and is lifted by handle 15. When the slide 14 is shifted upwardly the valve 18 is opened and air is thus permitted to enter the liquid containing chamber within the cup 7 to permit liquid to flow out through openings 9 when the cup is tipped.

The openings 9 are of such size as to permit an infant to drink at a safe and moderate rate of speed without danger of choking him and, of course, as soon as the handle 15 is released the valve 18 immediately closes, the air pressure preventing liquid from flowing out through outlet apertures 9.

It will be seen that I have provided a novel and highly efficient closure device for liquid containers adapted to normally close said container and adapted to controllably open said container to permit liquid to flow therefrom. The control means is responsive for opening the valve to the weight of the container when the same is lifted by said handle 15. The spring 20 permits the slide 14 to be easily shifted on trackway 13 while at the same time normally urging said valve 18 into closed position. The closure device 6 is attached in sealed relation to the container and forms an integral unit therewith which provides an excellent drinking cup for infants and small

children who are apt to accidentally tip the cup over or drop it on the floor.

It will, of course, be understood that various changes may be made in the form, details, arrangement and proportions of the parts without departing from the scope of my invention.

What I claim is:

1. An anti-spill liquid container comprising an open topped liquid confining cup, a top closure removably secured in sealed relation to the upper portion of said cup to normally close the top thereof, said closure having an outlet opening formed therein and a relatively small air vent formed therein in spaced relation to said outlet opening, a mounting bracket secured to one side of the closure, a slide mounted for substantially vertical shifting movement in said bracket, a valve fixed to the top of said slide and disposed in overlying alignment with said vent, a resilient element interconnecting said bracket and said slide for normally urging said slide into retracted position and said valve into seated position in said vent, and a gripping handle fixed to said slide to shift the same upwardly when said container is lifted by said handle.

2. An anti-spill device for liquid containers comprising a top closure constructed to be removably secured in sealed relation to the top portion of an opened top container, said closure having an outlet opening formed therein and a relatively small air vent formed therein in spaced

relation to said outlet opening, a mounting bracket secured to one side of the closure, a slide mounted for substantial vertical shifting movement in said bracket, a valve fixed to the top of said slide and disposed in overlying alignment with said vent, a resilient element interconnecting said bracket and said slide for normally urging said slide into retracted position and said valve into seated position on said vent, and a gripping handle fixed to said slide to shift the same upwardly when a container is connected to said closure and is lifted by said handle.
